United States Patent Office.

W. I. BLACKMAN, OF COLUMBUS, MISSISSIPPI.

Letters Patent No. 89,622, dated May 4, 1869.

IMPROVEMENT IN BOOK-BINDING.

The Schedule referred to in these Letters Patent and making part of the same.

To all whom it may concern:

Be it known that I, W. I. BLACKMAN, of Columbus, Lowndes county, Mississippi, have invented a new and useful Improvement in Book-Binding; and I do hereby declare that the following is a full, clear, and exact description thereof, which will enable others skilled in the art to make and use the same, reference being had to the accompanying drawings, forming part of this specification.

This invention relates to a new and useful improvement in binding books, and consists in securing the leaves, or sheets together by dovetail-ties, as will be hereinafter more fully described.

In the accompanying drawings—

Figure 1 represents a side view, showing the method of securing the leaves together, which, in ordinary book-binding is called "stitching."

Figure 2 shows an edge view of the same.

Similar letters of reference indicate corresponding parts.

A represents a book, (without a cover,) with the leaves secured together, according to my invention.

Instead of piercing the leaves, and passing through the twine, (as is usually done in book-binding,) I make two slits (as seen at B B, in fig. 1,) across the back, and also as seen, in fig. 2, at C C, leaving a dovetail

piece, D, between the slits. The fastening-twine is drawn down into these slits, where it is tightly glued and tied, after passing under it the tapes E, for fastening on the cover.

When the leaves of the book are thus fastened together, and the back A properly glued, the leaves are much more secure, and less likely to get loose, than when they are fastened in the ordinary manner. A leaf cannot be removed without tearing it.

This method does not increase the expense of ordinary book-binding, while the book is greatly improved as to its durability and usefulness.

Having thus described my invention,

What I claim as new, and desire to secure by Letters Patent, is—

In combination with a book, the slits B B, made in the back for receiving the fastening-twine, or thread, and securing the tapes E, substantially as and for the purposes herein shown and described.

The above specification of my invention signed by me, this 4th day of March, 1869.

W. I. BLACKMAN.
